UNITED STATES PATENT OFFICE.

OSCAR SMITH, OF REMER, MINNESOTA.

SLED-KNUCKLE.

No. 900,819.

Specification of Letters Patent.

Patented Oct. 6, 1908.

Application filed December 19, 1907. Serial No. 407,238.

To all whom it may concern:

Be it known that I, OSCAR SMITH, a citizen of the United States, residing at Remer, in the county of Cass, State of Minnesota, have 5 invented certain new and useful Improvements in Sled-Knuckles; and I do hereby declare the following to be a full, clear, and exact description of the invention, such as will enable others skilled in the art to which 10 it appertains to make and use the same.

This invention relates to a new and useful improvement in logging sleds.

The object of my invention is to provide a logging sled knuckle by means of which the 15 logging sled runner may be secured to the beam to permit a certain amount of rocking movement or play of the runners in passing over uneven ground and my invention comprises certain combinations and arrangements 20 as will be described more fully hereinafter.

In the accompanying drawings I have shown in Figure 1 a perspective view of a logging sled runner provided with my improved 25 sleigh knuckle. Fig. 2 shows an enlarged sectional view disclosing the beam in cross section and connected to the sleigh knee. Fig. 3 discloses a longitudinal sectional view of the beam with connected runner. Fig. 4 30 shows a top view of the runner cap as used in my invention, and Fig. 5 two runners connected to a cross beam.

My invention relates to that class of sleds known as logging sleds which are adapted to 35 carry very great loads and in connection with which all the parts must be sufficiently strong to withstand the great strain to which the sled is subjected.

In carrying out the object of my invention, 40 I use a solid runner 1 as shown in Fig. 1 of any conventional form which is provided in front with an opening 2 adapted to receive the usual cross bar of a suitable tongue. The forward end of the runner is reinforced upon 45 each side by means of a face plate 3 suitably secured, while extending from the heel of the runner and ending at the forward nose of the runner is the shoe 3 preferably secured by means of the bolts x which pass entirely 50 through the runner 1 as disclosed in Fig. 1. Secured to the runner 1 is an elongated metallic cap A having the side flanges 4, 4 and the horizontally extending flanges 5, 5 as clearly 55 shown in Figs. 1 and 3. At opposite ends this metallic cap is provided with the per-

forated securing ears 6, 6 while centrally is provided the upwardly extending lengthwise slotted cylindrical boss 7 the slot 8 of which is extended lengthwise of the cap as shown in Fig. 4. Near each end the cap is provided with the bolt openings 9, 9 as clearly shown in Figs. 2 and 4. Secured to this metallic cap is a curved rave B provided with the longitudinally disposed slot 10 and the securing ears 12, the ears being perforated and these 65 perforations registering with the cap perforations 9 so that suitable bolts 13 may be projected through the runner 1 through the cap openings 9 and ear perforations so that one set of bolts 13 will fasten the shoe 3, the 70 runner 1, cap A and rave B.

Held within the boss 7 as clearly shown in Fig. 2 is a head-provided pin 15 the head 16 of which is semi-spherical and snugly rides within the boss 7 and which further has a 75 reduced end 17 forming a shoulder v adapted to ride against the under surface of the rave slot as shown by Fig. 2. This pin 15 is carried by a suitable beam 20 having a bore into which bore the pin 15 is driven as also disclosed in Fig. 3. While I have shown and described but one sled knuckle, it is of course understood that two such beams 20 would be used in a logging sled as ordinarily constructed and that each beam would have such a sled 85 knuckle at each end.

Now logging sleds are used to carry very heavy loads so that a great strain is imposed upon the carrying and running gear and it is highly desirable that the running gear be 90 movable so that the runners may separately accommodate themselves to any irregularity of the surface over which the logging sled is dragged. In my invention when the sled encounters an obstruction in front the nose 95 is tilted upward and this movement is compensated at the knuckle in that the spherical boss 7 will properly ride within the dished seating 22 of a rub plate 23 as shown in Fig. 2 which rub plate is properly secured to the 100 under curved surface of the beam 20. The dished seating 22 is adapted to receive the boss 7 as is also shown in Fig. 3, the rub plate being suitably curved as disclosed in Fig. 2. Now as the pin 15 is carried by the beam 20 105 the upper part of the rave B would also be tilted backward and for this reason I provide the slot 10 which permits a free backward and forward tilting of the runner. From this, it will be seen that the boss 7, revolvably 110

carries the rub plate 23, permitting a free movement within certain limits of the sled runner.

The parts while made exceedingly strong 5 are simple of construction and can be readily assembled and dissembled in merely removing the bolts 13.

I am aware that it is not broadly new to 10 movably connect a sled runner to a cross beam, so I have confined my invention to a specific arrangement, embracing an upstanding boss, which revolvably carries a curved rub plate, and means to properly secure the working elements.

15 And having thus described my said invention what I claim as new is—

The combination with a sled runner, of a metallic cap having suitable end openings, projecting side flanges and a centrally disposed lengthwise slotted upstanding boss, a 20 curved rave having a central longitudinally projected slot and perforated ears, and secured lengthwise to said cap, said ear per-

forations registering with said cap openings, a curved rub plate having a central inwardly dished perforated seat carried and revolvably held upon said boss, a bore provided beam carrying said curved rub plate, a pin having a head at one end and a shoulder-forming reduced termination at the other, the under 25 surface of said pin head being spherical and movably held within said boss, and passing through said curved plate and bore and being carried by said beam, said reduced end being guided within said rave slot, and suitable 30 bolts passing through said ear perforations and cap openings and extending into said runner to secure said rave and cap, in the manner set forth.

In testimony whereof, I affix my signature, 35 in presence of two witnesses.

OSCAR SMITH.
